UNITED STATES PATENT OFFICE.

JOHN WESTALL, OF FALL RIVER, MASSACHUSETTS.

CRUDE-OIL BURNER.

1,293,590.

Specification of Letters Patent.

Patented Feb. 4, 1919.

Application filed October 22, 1918. Serial No. 259,192.

To all whom it may concern:

Be it known that I, JOHN WESTALL, a citizen of the United States, residing at Fall River, in the county of Bristol and State of Massachusetts, have invented certain new and useful Improvements in Crude-Oil Burners, of which the following is a specification, reference being had to the accompanying drawings.

10 This invention relates to an improved crude oil burner, and has for its primary object to provide a burner of this character primarily designed for use in connection with heating furnaces of either the hot air or hot water type, whereby the furnace may be economically operated.

It is a more particular object of the invention to provide a crude oil burner having simple and improved means for breaking up the partly vaporized oil and thoroughly mixing the same with air, whereby complete combustion will be obtained.

It is likewise another important object of the invention to provide an improved burner plate construction and a perforated oil supply coil, said burner plate being provided with a plurality of air openings, and a rotary gas breaker mounted and arranged with relation to the coil and the burner plate so as to create a forced draft of air through the burner plate and the mixture of the same with the partially vaporized oil.

And it is a further general object of the invention to provide a fuel oil burner as above characterized, which is simply and durably constructed, may be readily mounted in operative position within a furnace without requiring structural alterations in the latter, and which may also be manufactured and sold at comparatively small cost.

With the above and other objects in view, the invention consists in the improved construction, combination and relative arrangement of the several parts as will be hereinafter more fully described, subsequently claimed and illustrated in the accompanying drawings in which similar reference characters designate corresponding parts throughout the several views, and wherein:

50 Figure 1 is a side elevation illustrating the preferred embodiment of the invention;

Fig. 2 is a vertical sectional view;

Fig. 3 is a top plan view;

Fig. 4 is a section taken on the line 4—4 of Fig. 1; and

55

Fig. 5 is a perspective view of the gas breaker.

Referring in detail to the drawings, 5 designates the base plate, which is preferably formed with an upstanding annular 60 flange 6, and centrally provided with a hollow boss 7 to receive a bushing 8.

A second plate 9 is arranged above and in spaced relation to the base plate, and is likewise formed with an annular, upstanding flange 10. The flange of this plate is fixed to a plurality of vertically disposed supporting bars 11 which at their lower ends are integrally formed with, or suitably secured to, the flange 6 of the base plate. The 65 bars 11 extend for a considerable distance above the plate 9 and in their upper portions are provided with spaced openings 12. The body of the plate 9 is concave and inclines downwardly and inwardly from the marginal flange 10 to a central bearing boss 13 formed on said plate.

The burner casting 14, which is of cylindrical form, is adapted to be arranged between the upper ends of the vertical bars 11 80 and secured thereto by the bolts, shown at 15, which are engaged through the corresponding openings 12 in said bars in accordance with the desired height or elevation of the burner casting above the base plate.

85

16 designates the burner plate proper, which is corrugated to provide alternate ribs and grooves, and each of the ribs has a slot or opening 17 in the apex thereof. The corrugations do not extend across the entire diameter of the burner plate, which is provided with a plane, flat portion adjacent the annular body wall of the burner casting. Upon this flat portion of the burner plate, a single pipe coil 18 for the fuel oil is arranged and at one of its ends is provided with an elbow connection 19 extending radially through the wall of the burner casting. The other end of the pipe coil is closed. This coil is provided with a plurality of 90 spaced orifices 20, through which the fuel oil is discharged upon the corrugated burner plate.

95

This coil is provided with a plurality of 100 spaced orifices 20, through which the fuel oil is discharged upon the corrugated burner plate.

A vertically disposed shaft 21 is mounted

at its lower end in a suitable step bearing formed in the bushing 8 which extends upwardly through the bearing 13 on the plate 9 and also through a central opening in the 5 burner plate 16. The upper face of the bearing 13 is formed with a raceway for the bearing balls, indicated at 22, and a collar 23 fixed upon the shaft 21 is also provided with a similar raceway to receive the bearing balls. The shaft 21 is preferably hollow and to the same a belt pulley 24 is fixed. Around this pulley, a belt driven from a 10 motor or other suitable source of power is adapted to be engaged.

15 Upon the upper end of the shaft 21, and above the burner plate, the gas breaker or mixer 25 is fixed. This breaker consists of a plurality of radially disposed arms or blades which are integrally connected by the 20 central hub or sleeve 26, in which the upper end of the shaft 21 is engaged. This shaft is preferably hollow in order that it may be driven to rotate the gas breaker with a minimum expenditure of power. The arms 25 25 of the gas breaker are sufficiently long to extend outwardly to a position immediately above the coil 18.

In the event that the burner plate should be flooded with oil, the oil will flow downwardly through the openings 17 and drop upon the plate 9. As this plate is concave, the oil is directed inwardly toward the center thereof and is recovered and used, in the manner to be presently explained.

35 The oil supply pipe, shown at 27, which extends from the supply tank or reservoir is connected to the elbow 19, said pipe having a needle valve, indicated at 28, interposed therein, whereby the supply of fuel oil 40 to the coil 18 may be varied or regulated. A suitable pump actuated from the motor which operates the gas breaker may be employed for forcibly feeding the oil through the pipe 27 to the coil 18. 29 designates a 45 second pipe leading from the supply source to a pilot light 30, disposed closely adjacent to the perforated side of the coil 18. A valve 31 is also arranged in the pipe 29. 32 designates a drain pipe leading from the 50 plate 9 at a point adjacent its center in a downward direction to the overflow pipe which returns the oil from the pilot light to the supply tank. The oil for the pilot light is preferably supplied from an auxiliary 55 tank or reservoir by gravity. The pipe 33, however, leads from the burner to the main source of fuel supply. 34 indicates an automatically controlled cut-off valve in the fuel supply pipe 27, which is preferably actuated by a suitable thermostat. This 60 thermostat, however, constitutes no part of my invention and will not, therefore, be described in detail. It will, however, be understood that in case of failure of proper 65 operation of the thermostatically controlled

valve after the burner flame is extinguished, the excess oil will be drained by the overflow pipe 33 from the burner plate back to the main supply reservoir.

In the operation of my improved burner, 70 when the motor is started, oil first issuing from the coil 18 upon the burner plate is ignited by the pilot light 30 and the oil flowing through the coil 18 becomes quickly heated to a very high degree and partially 75 vaporized. In the operation of the motor, it will be understood that the oil breaker and mixer 25 is rotated at very high speed, and in the rotation thereof, air is drawn up through the openings 17 in the corrugated 80 burner plate. The oil gas is thoroughly broken up by the rotating blades or arms of the breaker and mixed with the air so that complete combustion of the hydrocarbon gas is assured. Thus, kerosene and 8 other relatively crude hydrocarbon oils may be utilized by means of the present invention for the heating of hot air or hot water furnaces. In the application of the burner to such use, the thermostatic means referred 9 to for the control of the oil supply valve 34 may also control the operation of the switch lever for the motor actuating the rotary gas breaker. Thus, in the event that the burner flame should be accidentally extinguished, 9 the thermostat will operate to cut off further supply of oil and open the motor switch. As above stated, however, in the event of failure of proper operation of the thermostatic means, the overflow pipe 33 will conduct the oil accumulating upon the burner plate back to the supply reservoir. The pilot light consuming any gas which may remain after the burner flame is extinguished, will prevent explosion which might otherwise occur from the accumulation of the gas. While I have referred to the invention principally designed for use in connection with heating furnaces, it is, of course, manifest that the device can also be advantageously employed for various other purposes. The several parts of the improved burner are all of relatively simple form and can be manufactured at small cost and easily and quickly assembled in their proper operative positions. The burner can be constructed in many different sizes in accordance with the purpose or use for which the same may be desired. The various elements above referred to are likewise susceptible of many modifications in their form, proportion and arrangement, and it is accordingly to be understood that I reserve the privilege of adopting all such legitimate changes as may be fairly embodied within the spirit and scope of the invention as claimed.

I claim:

1. In a crude oil burner, a burner plate, a plurality of openings therein, a perforated oil receiving pipe coil arranged upon the

5 marginal portion of said plate to deliver the oil thereon, and a rotary member mounted above the burner plate to break up the oil gas and mix the same with the air issuing through the opening in said plate.

2. In a crude oil burner, a body having a corrugated burner plate, each corrugation having an air opening therein, a perforated oil receiving pipe coil mounted upon the 10 marginal edge of said plate to deliver the oil upon the burner plate, and a rotary member mounted above the burner plate and having a plurality of radially disposed arms extending over the pipe coil to break up the oil 15 gas and mix the same with air issuing from said openings.

3. In a crude oil burner, a support, a burner body mounted in the support and having a corrugated burner plate, means for 20 delivering oil upon the burner plate, said burner plate being provided with a plurality of openings therein, and a rotary oil breaker mounted in the support and operating over the openings in the burner plate to break up 25 the oil gas and mix the same with air issuing from, said openings.

4. In a crude oil burner, a support, a burner body having a side wall mounted in the support and having a corrugated burner 30 plate, forming the bottom of the burner body, means for delivering oil upon the burner plate, said burner plate being provided with a plurality of openings therein, extending through the corrugations, a rotary oil 35 breaker mounted in the support and operating over the openings in the burner plate to break up the oil gas and mix the same with the air issuing from said openings, and an additional oil retaining plate mounted in the 40 support beneath the burner plate to receive excess oil flowing through said openings.

5. A crude oil burner having an upstanding side wall and a corrugated bottom, the bottom having perforations passing through 45 the crests of the corrugations, means for delivering oil at intervals around the circumference of the bottom, and a power rotated shaft passing upward through the bottom

and having radial blades disposed above the bottom.

6. A crude oil burner having a bottom formed with corrugations, the bottom having perforations passing through the crests of the corrugations, an oil supply pipe entering the burner and extending circumferentially around the bottom and perforated at intervals to permit the entrance of air, an oil receiver mounted below the bottom of the burner in spaced relation thereto and receiving the drip from said perforations, and a 55 drainage pipe extending from said oil receiver.

7. A crude oil burner having a bottom formed with corrugations, the bottom having perforations passing through the crests of 60 the corrugations, an oil supply pipe entering the burner and extending circumferentially around the bottom and perforated at intervals to permit the entrance of air, an oil receiver mounted below the bottom of the 65 burner in spaced relation thereto and receiving the drip from said perforations, and a drainage pipe extending from said oil receiver, and a power driven shaft passing upward through the receiver and the bottom 70 of the burner and having radial blades disposed adjacent the bottom and above the same.

8. A crude oil burner including a burner plate having an upstanding surrounding side 75 wall, the burner plate being formed with upstanding corrugations and with perforations extending through the crests of the corrugations, means for supplying oil at a plurality of points around the margin of the 80 burner plate to said plate, and power operated means disposed above the burner plate for sucking air up through the perforations and mixing the air with the burning oil.

In testimony whereof I hereunto affix my 85 signature in the presence of two witnesses.

JOHN WESTALL.
